UNITED STATES PATENT OFFICE.

EDGAR POHLIG, OF PHILADELPHIA, PENNSYLVANIA.

BASE-BALL-GAME BOARD.

1,042,142.

Specification of Letters Patent.

Patented Oct. 22, 1912.

Application filed February 6, 1912. Serial No. 675,767.

To all whom it may concern:

Be it known that I, EDGAR POHLIG, a citizen of the United States, residing at Philadelphia, in the county of Philadelphia and State of Pennsylvania, have invented certain new and useful Improvements in Base-Ball-Game Boards, of which the following is a specification.

My invention relates to improvements in baseball game boards, the object of the invention being to provide an improved construction of field, containing fielder, batter, runner, battery and umpire positions, together with improved means for keeping the score, and improved means for supporting strips or blocks indicating the players of the contesting teams.

A further object is to provide a game board which is adapted to be utilized for the playing of a baseball game in connection with a suitable chance device (not shown) and so construct the board that when utilized in connection with men and counters may be operated to indicate practically every play that is made upon a baseball field.

With these and other objects in view, the invention consists in certain novel features of construction and combinations and arrangements of parts, as will be more fully hereinafter described and pointed out in the claims.

In the accompanying drawings: Figure 1, is a plan view of my improved baseball game board. Fig. 2, is a view in section on the line 2—2 of Fig. 1. Fig. 3, is a rear view of one of the player strips. Fig. 4, is a view of one of the men which may be utilized in playing the game. Fig. 5, is a view 40 of an indicator pin, and Fig. 6, is a view in section on the line 6—6 of Fig. 1.

My improved game board may, of course, be constructed of various materials which on its upper face constitutes a field 1 having thereon a representation of a baseball diamond 2, containing the representation of a home plate 3, first base 4, second base 5, and third base 6. The home plate and the several bases are connected by ordinary base lines, and suitable spaces 7 and 8 are provided for the catcher, pitcher and umpires. In space 7, an opening 9 is provided to receive a man 9^a as shown in Fig. 4 to represent the catcher, while of course I would 55 employ as many of such men 9^a as necessary to play the game. I have indicated

only one, as they are all precisely alike with the exception of ornamentation to more clearly show the position the player occupies and to distinguish men of different teams. In the space 8, an opening 10 is provided to receive the figure representing the pitcher, and while I shall refer to these figures by their names known in baseball, it is to be understood that I use such terms to indicate figures. Back of the catcher's position 9, an opening 11 is provided for the reception of a figure to represent an umpire, and an opening 12 is provided back of the pitcher's position 10 for a second umpire. 60 Back of the base lines, between first and second, and second and third bases, openings 13, 14, 15, and 16 are provided, and are adapted to support figures representing the first basemen, the second basemen, the short 65 stop, and the third basemen. In addition to these positions for the infielders, I provide four openings 13^a, 14^a, 15^a, and 16^a inside the base lines, and into these openings the fielders are to be placed when a runner 70 is on base, so as to give the play a natural appearance. Outside of the diamond 2, openings 17, 18, and 19 are provided for the figures representing the right fielder, center fielder, and left fielder respectively. The 75 representations of the home plate 3 and the bases 4, 5, and 6, each have openings to receive the figures, and in all instances above described where the openings are provided, 80 suitably marked spaces are inclosed around 85 the openings so as to give a more attractive appearance to the field.

It will be noted that the figures 9^a have tapered lower ends 20, so that they may be readily moved into the openings and securely held in vertical position. In one end of the field, at opposite sides of the same, recesses or pockets 21 are formed to receive cards 22 containing the names and positions of the players on a ball team, and these 90 cards 22, on their rear faces, are marked with the name of the club back of each player's name, so that the cards may be cut on the lines 23 between the name, so as to allow the said names to be differently arranged to 95 suit the fancy of the player.

Lines of openings 24 are provided beside the recesses 21 to receive the fingers representing the players who are having their 100 inning, figures representing the other team 110 being in position on the field. At the opposite end of the board, horizontal and verti-

cal lines 25 and 26 respectively divide the field into two sets of spaces, one set for each team. That is, each set of spaces comprises three horizontal rows, the spaces of the intermediate row containing numerals from one to ten, the first space of said row being free from any numeral. The upper and lower rows of said spaces are formed with openings 27 to receive pins 28 constituting counters. At the left hand end of each upper and lower row, the words "innings" and "runs" appear, so that counters 28 are provided for each row, the first position of said counters at the extreme left being a rest position, and they are moved to the right in accordance with the number of innings played, and the number of runs made as will be understood. In this end of the field also four spaces 29 are provided under the caption "outs". Three of these spaces are numbered "1", "2", and "3", while the first space to the left constitutes a rest space, and they are all provided with openings 30 to receive counters 28.

25 While this particular game board is not limited to any particular rules for playing the game, yet in order that a clear understanding may be had of the functions of the construction, I will give below a brief description of several plays.

When the game starts, the players of one team will be in their proper positions on the field. The umpires will also be in their positions, and the batter will be at the home plate 3. In accordance with the operation of a suitable chance device, if the batter makes a hit, he will be moved to first base, and the new batter placed at home plate. The first baseman will then be moved inward from the opening 13 to the opening 13^a which is the position he would normally assume in a game. If a runner is on third base with less than two out, the infielders would all take their positions on the inside 40 of the base lines. This is a position they would normally take under such conditions to endeavor to cut off the impending run. By thus providing two positions for all of the infielders, the appearance of the game 45 very closely resembles that of an ordinary game. If an out is recorded, a pin or counter 28 is moved from the first space to the left of the series of spaces 29 to the space marked 1, and by moving this counter 28, 50 the number of outs may be kept so that there may be no dispute when an inning is over.

By means of counters 28 in the openings 55, an accurate record of innings and runs may be kept by simply moving the pins from one space to another. The team which is at bat will have its players in the openings 24, so that each player will take his position at bat in regular order, and if desired 60 the lineup may be changed in the course of

a game, so as to bring a well known pinch hitter to bat at an opportune time.

The board therefore may be utilized to play a game of base ball, carrying out to a maximum degree, the plays which are made 70 upon a baseball field, and by positioning the players in accordance with the play, the board will give the appearance of the fielders, and runners in action, and thus lend an interest to the game.

75 While I refer to the several player positions as openings, I would have it understood that this term is used in its broadest possible sense in order to provide a pocket to receive the lower end of the figure 9^a, and hold said figure in an upright position.

The invention is therefore not limited to the precise details set forth, but I consider myself at liberty to make such change and alterations as fairly fall within the spirit 85 and scope of the appended claims.

Having thus described my invention, what I claim as new and desire to secure by Letters Patent is:

1. A baseball game device, comprising a 90 plurality of name spaces containing words indicating ball players, and other spaces formed beside the name spaces to contain the pieces indicating players of the team at bat, substantially as described.

95 2. A game board comprising a field, lines on said field forming the representation of a baseball diamond, figures at the angles of said diamond representing the home plate, first, second and third bases respectively, 100 and positions indicated on said board for the infielders, two positions being provided for each infielder, one set of positions outside the diamond and the other set inside the diamond, substantially as described.

105 3. A game board comprising a field, lines on said field forming the representation of a baseball diamond, figures at the angles of said diamond representing the home plate, first, second and third bases respectively, 110 and positions indicated on said board for the infielders, two positions being provided for each infielder, one set of positions outside the diamond and the other set inside the diamond, said home plate, said bases, 115 and said infielder positions having openings therein for the reception of game pieces, substantially as described.

120 4. A game board comprising a field, lines on said field forming the representation of a baseball diamond, figures at the angles of said diamond representing the home plate, first, second and third bases respectively, and positions indicated on said board for the infielders, two positions being provided for 125 each infielder, one set of positions outside the diamond and the other set inside the diamond, said home plate, said bases, and said infielder positions having openings therein for the reception of game pieces, 130

positions indicated on said field for the pitcher and catcher and umpires, and for the out fielders similar to the positions above described for the infielders, and means on 5 the board for keeping account of the runs and innings, substantially as described.

5. A game board comprising a field, lines on said field forming the representation of a baseball diamond, figures at the angles of 10 said diamond representing the home plate, first, second and third bases respectively, and positions indicated on said board for the infielders, two positions being provided for each infielder, one set of positions outside 15 the diamond and the other set inside the diamond, said board constructed to receive cards containing the names of players, and positions on the board beside the cards for the reception of game pieces indicating 20 the players, and said board ruled, and provided with openings for the reception of pin counters, whereby lines of openings are formed to indicate the innings, and runs, substantially as described.

25 6. A game board comprising a field, lines on said field forming the representation of a baseball diamond, figures at the angles of said diamond representing the home plate, first, second and third bases respectively, 30 and positions indicated on said board for the infielders, two positions being provided for each infielder, one set of positions outside the diamond and the other set inside the diamond, said home plate, said bases, and 35 said infielder positions having openings therein for the reception of game pieces, said board constructed to receive cards containing the names of players, and openings formed in the board beside the cards for the 40 reception of game pieces indicating the players, and said board being ruled to form lines of spaces to record the innings and runs and the several spaces each being provided with an opening to line a pin counter, and there 45 being rest openings or spaces provided at the left of each series of openings, substantially as described.

7. In a base ball game apparatus, a board having delineated thereon the representation 50 of a base ball field, there being places indicated at the home plate and the three bases respectively to receive markers indicating players, a plurality of markers representing the players, a line up of a team, a designated 55 space on the board for said line up, and there being places opposite each name in the line up to receive the said markers, said

markers being adapted to be played from the places at the line up to the places on the field, substantially as described.

60

8. In a base ball game apparatus, a board having delineated thereon the representation of a base ball field, there being apertures provided at the home plate and the three bases respectively to receive the markers indicating players, a recess to receive the names of the line up of a team and there being an aperture opposite each name in the line up, in combination with a corresponding number of markers indicating players, 70 said players being adapted to be played from the apertures at the line up to the apertures on the field, substantially as described.

65

9. In a base ball game apparatus, a board having delineated thereon the representation of a base ball diamond, there being places indicated at each of the positions normally assumed by the players of the side in the field, there being other places indicated at the home plate and the three bases respectively, there being a designated space to receive the line up of each team, and an indicated place opposite the position for each name in the line up, and two sets of markers, one for each team, each comprising a plurality of pieces representing players and a marker piece adapted to be positioned in the place opposite the name of the next man at the bat of the respective sides at the next 80 inning.

75

10. In a base ball game apparatus, a board having delineated thereon the representation of a base ball diamond, there being apertures provided at each of the positions normally assumed by the players of the side in the field, there being other apertures provided at the home plate and the three bases respectively, said board being provided with a pair of recesses to receive the line up of the two teams, there being an aperture opposite 95 the position for each name in the line up, and two sets of markers, one for each team, each comprising a plurality of pegs representing players and a marker peg adapted to be positioned in the aperture opposite the 100 name of the next man at the bat of the respective sides at the next inning.

90

In testimony whereof I have signed my name to this specification in the presence of two subscribing witnesses.

EDGAR POHLIG.
